HERMANN ILENBURG, OF PHILADELPHIA, PENNSYLVANIA, AS SIGNOR TO MACKELLAR, SMITHS, AND JORDAN.

Design No. 3,270, dated December 1, 1868.

DESIGN FOR PRINTERS' TYPE.

The Schedule referred to in these Letters Patent and making part of the same.

To all whom it may concern:

Be it known that I, HERMANN ILENBURG, (assignor to MACKELLAR, SMITHS, and JORDAN,) of the city and county of Philadelphia, Pennsylvania, have originated and designed a new Design for a Printing-Type, of which the following is a full, clear, and correct description, reference being had to the accompanying specimens, in which an entire alphabet, of large and small letters, is shown, made in accordance with my design, which design is preserved in the figures, signs, and symbols that may accompany the same.

Having thus described my invention,

What I claim as new, and desire to secure by Letters Patent, is—

The design for printing-type, as shown and set forth.

Witnesses: HERMANN ILENBURG.
